OXYGEN DILUTER FOR BREATHING MASKS

Claude A. Vidal, Los Angeles, Calif., assignor to
American Hospital Supply Corporation

Filed Jan. 13, 1975, Ser. No. 540,389

Term of patent 14 years

Int. Cl. D23—99; D24—02

U.S. Cl. D23—4

FIG. 1 is an end view of the diluter taken along line 1—1 of FIG. 3;

FIG. 2 is an end view taken along line 2—2 of FIG. 3;

FIG. 3 is a side view taken along line 3—3 of FIG. 1;

FIG. 4 is an opposite side view taken along line 4—4 of FIG. 1;

FIG. 5 is a top view taken along line 5—5 of FIG. 1;

FIG. 6 is a bottom view taken along line 6—6 of FIG. 1.

I claim:

The ornamental design for an oxygen diluter for breathing masks, substantially as shown.
